WATER PRESSURE REDUCER

Algernon E. Butts, Houston, Tex.

Application January 12, 1939, Serial No. 250,614

2 Claims. (Cl. 137—78)

This invention relates to a water pressure reducer especially adapted for use on a hot water system employed for furnishing hot water for any purpose and which includes a safety valve required by law to prevent pressure from building up to such an extent that would endanger the system. A system of this kind frequently discharges hot water from the storage tank thereof by way of the safety valve when the flow of hot water from the system is suddenly stopped at the hydrant due to back pressure suddenly building up against the pressure of the incoming water from the water main causing an upward surging of water in the tank that builds up an excessive pressure sufficient to open the safety valve and permit the water to escape and cause damage. The present invention has for its primary object the provision of means for automatically reducing the pressure of the incoming water from the water main when the back pressure occurs and obviates the surging upwardly of the water in the supply tank and consequently eliminates the temporary excessive pressure which heretofore acted to open the safety valve and permit waste of the water as well as damage.

With these and other objects in view, the invention consists in certain novel features of construction, combination and arrangement of parts to be hereinafter more fully described and claimed.

For a complete understanding of my invention, reference is to be had to the following description and accompanying drawings, in which

Figure 1 is a fragmentary side elevation illustrating a conventional water heating arrangement equipped with a water pressure reducer constructed in accordance with my invention.

Figure 2 is a fragmentary vertical sectional view illustrating the water pressure reducer.

Figure 3 is a sectional view taken on the line 3—3 of Figure 2.

Figure 4 is a perspective view illustrating a plunger type valve element.

Figure 5 is a perspective view illustrating a plunger type piston.

Referring in detail to the drawings, the numeral 5 indicates a storage tank of a hot water heating system, 6 the outlet pipe of said tank equipped with the usual hydrant or faucet 7 for obtaining hot water from the supply tank as needed. Connected with the supply tank 5 is a conventional type of heater 8 for the purpose of heating the water in the supply tank to a desired temperature. The tank 5 by the requirement of law must be equipped with a safety valve

9 so that should excessive pressure build up in the tank it may escape. A water supply pipe 10 is connected with the tank and to a water main 11 for furnishing water to the tank as water is drawn from the tank by way of the faucet 7. It has been found in actual practice that when the faucet 7 is quickly closed a back pressure is suddenly created in the tank against the pressure of the incoming water causing an upward surging of water in the supply tank sufficient to build in 10 an excessive pressure causing the valve 9 to open and allow waste of water and damage. To overcome this objection to a water heating system of the character described the present invention is connected thereto between the water supply pipe 15 10 and the water main 11 so that when the back pressure is created in the supply tank by the sudden closing of the faucet 7 the supply of water to the tank from the water main will be automatically and temporarily cut off. The 20 water main remains closed to the tank 5 by the present invention until the upward surging of the water in the tank 5 has stopped and the present invention then automatically restores the communication of the water main to the 25 tank 5 by way of the water supply pipe 10.

The present invention consists of a valve housing 12 threaded onto the water main 11 at its lower end and is equipped at said end with a valve seat 13 of tubular construction having a 30 series of ports 14 and in which is slidably mounted a plunger-type valve 15 provided with a stem 16. The ports 14 are opened and closed by the sliding movement of the valve element 15. The valve housing 12 has an outlet neck 17 35 and a stuffing box 18 including a guide 19. The stem extends through the stuffing box 18 and the guide 19 and has mounted thereon a coiled spring 20, one end of which bears against the guide 19 and the other end against the collar 21 fixed on the stem. The spring 20 normally acts to position the valve element 15 to close the ports 14 40 while the flow of water from the main acts on the valve element 15 to slide the same upwardly against the action of the spring 20 to open the 45 ports 14.

The neck 17 is connected to a T-coupling 21 by a nipple 22. The T-coupling 21 is connected to the water supply pipe 10 and also has connected thereto a by-pass pipe 23 which is in turn 50 connected to a vertically arranged cylinder 24 located above and in alignment with the stem 16 of the valve element 15 and is provided with a stuffing box 25. A plunger type piston 26 is slideable in the cylinder 24 and extends through the 55

stuffing box 25 to contact the upper end of the stem 16 of the valve element 15. The water pressure in the by-pass pipe 23 normally maintains the piston 26 in contact with the stem 16 of the valve element 15.

Under normal operating conditions, the valve element 15 is in its uppermost position, as shown in Figure 2, to open the ports 14 so that water from the main may reach the supply tank 5. 10 The valve element 15 remains in this position as long as conditions are normal and water is being drawn from the supply tank by way of the faucet 7. However, when the faucet 7 is suddenly closed, stopping the flow of incoming water, the 15 spring 20 moves the valve element 15 downwardly closing the ports 14 cutting off the supply of water to the tank 5 and thereby eliminating the possibility of the water being caused to surge upwardly and bring about building up of excessive pressure 20 in the tank sufficient to open the safety valve. When the faucet is opened the pressure of water raises the valve 15 to open ports 14 and thereby restore the supply of water to the tank 5.

While I have described and shown a plunger 25 type valve 15 and a cylindrical type seat, it is to be understood that this invention can successfully operate with another type of valve element and valve seat. Also, it is to be understood that while this invention has been shown and described in 30 connection with a hot water heating system of a particular construction, the invention is readily adaptable to other types of systems.

It is believed that the foregoing description, when taken in connection with the drawings will 35 fully set forth the construction and advantages of this invention to those skilled in the art to which such invention relates, so that further detailed description will not be required.

What is claimed is:

1. In a device of the class described, a hot water supply tank having a safety valve, a supply line for said tank, valve controlled delivery means leading from said tank, and means for preventing opening of the safety valve when back pressure is developed in said tank by the sudden closing of the valve controlled delivery means, comprising a casing in the supply line to said tank and having a valve seat, a valve in said casing adapted to 5 engage said seat and provided with a stem and tending to be opened by the supply line pressure, spring means to normally maintain said valve seated, a cylinder having a piston therein for applying pressure to said stem in opposition to the opening pressure, the valve, stem and piston being so constructed that the areas thereof tending to effect opening of the valve by pressure are equal to the areas tending to close said valve by pressure. 20

2. In a device of the class described, a water supply tank having a safety valve, a supply line for said tank, valve controlled delivery means connected to said tank, and means for preventing opening of the safety valve when back pressure is developed in said tank by the sudden closing of the valve controlled delivery means comprising a valve in the supply line to said tank tending to be opened by the supply line pressure, means acting to normally maintain said valve closed, and means for applying pressure to said valve in opposition to the opening pressure, said last-mentioned means being so constructed that the areas thereof tend to effect closing of said valve by pressure equal to the areas tending to open said valve by pressure. 25 30 35
